UNITED STATES PATENT OFFICE.

WILLIAM COLIN RUSSELL, OF EAST SHEEN, ENGLAND.

ADJUSTABLE PROPELLER DEVICE.

1,418,399.

Specification of Letters Patent. Patented June 6, 1922.

Application filed December 16, 1919. Serial No. 345,300.

To all whom it may concern:

Be it known that I, WILLIAM COLIN RUSSELL, a subject of the King of Great Britain, residing at East Sheen, in the county of Surrey, England, have invented certain new and useful Improvements in Adjustable Propeller Devices, of which the following is a specification, reference being had thereto in the accompanying drawings.

10 It is known that the general efficiency and utility of airscrews used for the propulsion of aircraft can be increased by providing means of adjusting the angles of the air-screw blades to various angles about their longitudinal axis during flight, to agree with changes in the speed of the aircraft or fluctuation of engine power output, and a number of constructions to this end have already been proposed.

20 My invention has for its object to provide improved means of pivoting, mounting and controlling the blades of an adjustable air-screw of the type having the pivots of diametrically opposite blades telescoped one 25 within the other for the purpose of reducing bulk, and embodies the following constructional features.

Diametrically opposite blades constituting a balanced working pair are each mounted upon or formed in one with a pivot, the pivot of the one being telescoped within the pivot of the other and the pair supported in position in the following manner.

An inner tubular or solid pivot is passed 35 through an outer tubular pivot and arranged to project beyond the farther end (or normal diameter) of outer pivot stem for the purpose of forming upon or attaching to the portion so projecting a head piece arranged so that between the said headpiece and the adjacent end of outer pivot stem can be provided a thrust bearing (preferably a ball bearing) for the purpose of interlocking the pair of pivots longitudinally.

40 45 50 55 60 65 70 75 80 85 90 95 100 105 110

while leaving each pivot freedom to rotate independently about its longitudinal axis. Journal bearings are provided between the inner and outer pivots to support them laterally but with freedom to rotate about their longitudinal axis. Either of or both the pivots or interlocking headpiece may be constructed of two or more parts for the purpose of assembling them in working position. Each pivot may be formed in one with its blade, or may be constructed with an end

plate to which a detachable blade can be secured.

The said pair of pivots (or in a four bladed airscrew, two pairs of pivots at right angles to each other) is mounted in journal bearings in a supporting frame or **T** head 60 constituting the airscrew hub mounted upon or formed in one with the airscrew shaft, each pivot being free to rotate independently about its longitudinal axis, and each pair of pivots is arranged in the said supporting frame or **T** head so that the inner pivot is wholly supported within the outer pivot, the latter being wholly supported within the frame; or alternatively, so that each pivot of the pair is supported partially within or upon its fellow pivot and partially directly within the said supporting frame or **T** head upon airscrew shaft.

70 75 80 85 90 95 100 105 110

The two blades and pivots are arranged to be balanced in weight, and the radial pull on each blade and pivot due to centrifugal force during rotation of the airscrew is thus wholly taken up by the interlocking thrust bearing between the pivots.

Levers may be attached to or formed upon the pivots for the purpose of revolving them to effect blade adjustment.

Where use is made of detachable blades constructed of wood or other frail material, arranged with conical or tapered butt ends (having their larger diameter inmost) enclosed in similarly conical or tapered split metal sockets as a means of attaching the blades to their pivots, I may provide the following special means of securing the split sockets to the blade butts. In lieu of forming the respective split parts of the sockets with flanges by which they may be secured together by bolts and nuts as hitherto proposed, the conical or tapered portions of split sockets are attached to the blade butts by means of winding them around with metal wire or tape of high tensile strength, said wire or tape windings serving the purpose of meeting the heavy bursting stress in the socket arising from the wedging action of the tapered blade butt when acted upon by centrifugal force during rotation. The

110 split sockets may be provided with circumferential flanges or grooves at suitable intervals to prevent the wire windings from slipping. The use of metal wire or tape socket binding as proposed has a special value under the conditions of working of revolving

airscrew blades in securing maximum strength with minimum weight, and it is obvious that this construction is not dependent upon any particular form of pivot 5 mounting.

In order that the arrangement of blade mounting and pivoting embodied in my invention may be the better understood the construction is further explained by reference to the drawings appended hereto in 10 which

Figures 1 and 2 are respectively a transverse section and an elevation of a pair of detachable blades and pivots the blades 15 being fixed by wire bound sockets bolted to the pivot plates, the inner pivot having a detachable end by means of which the thrust bearing is secured in position and the blade adjustment being effected by means of a pair 20 of annular gear wheels operated by band brakes.

Figure 3 is a corresponding horizontal cross section thereof.

Figure 4 is a transverse section of an engine shaft of current type illustrating a modified arrangement of helically grooved wheel and inner pivot in conjunction with roller journal bearings.

In Figs. 1, 2 and 3 the airscrew shaft A 30 is in this illustration of my invention formed in one with a tubular T headpiece A¹ in which is supported in journal bearings, with freedom to rotate about its longitudinal axis, the outer tubular pivot B terminating in the 35 end plate B¹ to which one of the airscrew blades may be bolted. Through the said hollow pivot B is passed the inner pivot C similarly supported therein in journal bearings with freedom to rotate about its longitudinal axis, and upon the end of it opposite to B¹ is formed a similar end plate C¹ to which the other airscrew blade of the pair may be bolted. The projecting end of the inner pivot C adjacent to the end plate B¹ 40 is formed as a screw upon which is screwed the nut head C³ arranged so that between it and the top of the stem of pivot B (or end plate B¹) may be located the thrust bearing C⁴ illustrated in this drawing as a ball bearing. The nut head C³ and thrust bearing C⁴ thus complete the interlocking of the pivots B and C and each pivot is independently revolvable about its longitudinal 45 axis by means of the levers B² and C². I do not limit myself to any particular means of operating these levers to effect blade 50 adjustment.

To the end plates B¹ and C¹ are bolted the conical metal sockets P split (in halves 55 in this illustration) so that they may be placed around the similarly conical butt ends R formed upon the wooden blades. The sockets P are secured to the butt ends R by being bound around with wire or tape 60 of high tensile strength, the windings P²

being placed in the grooves formed between the flanges P¹ on the sockets P, the flanges being provided to prevent the windings slipping up the tapering face of the socket.

In Fig. 4 upon the engine shaft A (which 70 is of current aero engine type and not a special T headed shaft as shown in Figs. 1, 2 and 3) is mounted a duplex frame A¹ carrying bearing rings A² and A³ in which the pivot stems are supported in roller bearings. The inner pivot C is here illustrated as a bar with a tapering and screwed end, and the end plate C¹ (formed with a sleeve to fit over the inner bar C) is secured to it by a nut C⁵. The head C³ bearing upon the 80 thrust ball bearing C⁴ is formed in one with the bar C, the illustration emphasizing that the arrangement of the pivots to embody the interlocking thrust bearing may be varied whilst retaining the general feature of interlocking telescoped pivots by a thrust bearing 85 irrespective of how the latter is arranged. In the mounting of the pivots in the supporting frame, the neck of outer pivot B is supported in the roller bearing ring A² 90 and its body is further supported on bearings upon the inner pivot C. The neck of inner pivot C is supported in the roller bearing ring A³ and its body on bearings within the outer pivot B, thus illustrating 95 that the pivots may be mounted partially directly with the supporting frame and partially within or upon each other.

For the purpose of operating the pivot 100 adjusting levers of airscrews having the pivots of diametrically opposite blades telescoped one within the other, I provide the following device as an alternative to other known arrangements, the object of my improvement being to obtain synchronized 105 movement of the blade levers in opposite directions, with means for rapidly synchronizing the setting, and an irreversible operating mechanism whereby it is not necessary to maintain revolving parts under continuous pressure or tension for the purpose of holding the blade levers in any desired position.

To this end I attach levers to each pivot 110 of a working pair of blades arranged so that pins or the like located at the extremities of the levers may engage substantially at diametrically opposite sides in or against a groove or cam face cut in a drum or wheel 115 revolvably mounted between the levers, the said grooved or cam faced drum or wheel being so arranged that its rotation causes equal and opposite movement of the pivot levers. Preferably I may employ a grooved 120 drum having a groove of uniform pitch cut in its periphery giving left hand movement for one half the circumference and right hand movement for the remaining half i. e. the groove is endless traversing from one side of the drum to the other and back 125 130

again, so that pins engaging at diametrically opposite points will, when the drum is rotated, be moved equally but oppositely. Alternatively similar motion may be imparted by means of a disc tilted in relation to its axis of rotation.

For convenience in securing perfectly synchronized blade setting, adjusting screws may be provided whereby the said grooved wheel or drum can be adjusted longitudinally in relation to its axis.

Motive power for rotating the said grooved wheel or drum in either direction may be provided by any convenient form of gearing, but arranged preferably with the final drive to the drum conveyed through a worm and worm wheel in order that the drum may be completely irreversible by any pressure from the pivot levers.

20 The construction is more fully explained by reference to drawings Figs. 1, 2, 3 and 4 appended hereto.

In Figs. 1, 2 and 3, the blade pivots have attached to them levers B² and C² terminating respectively in the pins B²¹ and C²¹ which engage in a helical groove D¹ cut in the drum D which is mounted between the said pins upon an axle D² so that the pins engage at diametrically opposite points in its periphery. Figs. 2 and 3 show the groove cut uniformly with right hand movement for half the circumference of drum D and left hand or reverse movement for the remainder, thus when the drum D is rotated upon its axle D² the pin and lever B² is moved in one direction and the pin and lever C² in the opposite direction an approximately equal distance. Adjusting screws D³ permit of adjustment of the drum setting axially.

45 The drum D is here illustrated as having attached to it a worm wheel D⁴ driven by the worm E¹ mounted upon the driving shaft E located at the side of airscrew hub and driven either forward or backward by mechanism of any convenient type provided for this purpose and not illustrated herein.

The drum D is illustrated as mounted across the axis of rotation of the airscrew 50 for convenience of rotational balance. In Fig. 4 the drum D is mounted in an alternative position, illustrating that the drum may be mounted in any convenient position.

I claim:—

55 1. The combination with a propeller shaft and a propeller having blades pivotally mounted in the propeller hub, of a tubular pivot formed with an end plate, a conical split metal socket secured to said plate in which socket the butt end of one of the blades is secured, a winding of high tensile strength about said socket, an inner pivot passing through and supported in the tubular pivot and formed with an end plate, a conical split metal socket secured to said end plate

in which socket the butt end of the other of the blades is secured, a winding of high tensile strength about said socket, a laterally extending lever on each of said pivots, a nut head on the projecting end of the inner pivot, a thrust bearing between the said head and the end of the tubular pivot, and means actuated by the propeller shaft for operating the said laterally extending levers so as to turn the said pivots in opposite directions in the propeller hub.

2. The combination with a propeller shaft and a propeller having blades pivotally mounted in the propeller hub, of a tubular pivot formed with an end plate, a conical split metal socket secured to said plate in which socket the butt end of one of the blades is secured, said socket having grooves on the exterior thereof, windings of high tensile strength in said grooves about said socket, an inner pivot passing through and supported in the tubular pivot and formed with an end plate, a conical split metal socket secured to said end plate in which socket the butt end of the other of the blades is secured, said last named socket having grooves on the exterior thereof, windings of high tensile strength in said grooves about said socket, a laterally extending lever on each of said pivots, a nut head on the projecting end of the inner pivot, a thrust bearing between the said head and the end of the tubular pivot, and means actuated by the propeller shaft for operating the said laterally extending levers so as to turn the said pivot in opposite directions in the propeller hub.

3. The combination with a propeller shaft and a propeller having blades pivotally mounted in the propeller hub, of a tubular pivot supported in journal bearings in the propeller hub and formed with an end plate to which one of the blades is attached, an inner pivot passing through and supported in journal bearings in the said tubular pivot and formed with an end plate to which the other of the blades is attached, a nut head on the projecting end of the inner pivot, a thrust ball bearing between the said head and the end of the tubular pivot, a laterally extending lever on each of said pivots, a terminal pin on each of said levers, a helically grooved drum for engagement by said pins, means for adjusting said drum longitudinally in relation to its axis, and means actuated by the propeller shaft for operating the said drum so as to deflect said levers and turn the said pivots in opposite directions in the propeller hub.

4. The combination with a propeller shaft and a propeller having blades pivotally mounted in the propeller hub, of an outer tubular pivot supported partly in a hub roller bearing ring, an inner tubular pivot also supported partly in a hub roller bearing ring said pivots being also partly sup-

ported in journal bearings the one within the other, an end plate on each of said pivots to which the propeller blades are respectively attached, a nut head, a thrust ball bearing between said head and the end of the outer tubular pivot, a laterally extending lever on each of said pivots, a terminal pin on each of said levers, a helically grooved drum for engagement by said pins, means for adjusting said drum longitudinally in relation to its axis, and means actuated by the propeller shaft for operating said drum so as to deflect said levers and turn the said pivots in opposite directions in the propeller hub.

5. In a revoluble variable pitch propeller

for aircraft, the combination with the propeller shaft having telescopic blade pivots, of a mounting for said pivots consisting of a frame mounted on the propeller shaft, and 20 antifriction rings on said mounting, each of which embraces the neck portion of one of the pivots, the shaft portions of said pivots being borne by journal bearings respectively within and upon each other. 25

In testimony whereof I affix my signature in presence of two witnesses.

W. COLIN RUSSELL.
